ANALYTICAL SYSTEM

Reed C. Lawlor, Alhambra, Calif., assignor to Consolidated Engineering Corporation, Pasadena, Calif., a corporation of California

Application July 31, 1942, Serial No. 453,128

3 Claims. (CL 73—18)

My invention relates to mass spectrometry, and more particularly to the analysis of a chemical mixture containing a plurality of components which upon ionization may form ions having the same mass-to-charge ratio. More specifically, my method makes possible the analysis of such a mixture by taking into account the fact that such ions are usually produced in different proportions from such components at different ionization voltages.

This application is a continuation-in-part of copending patent application, Serial No. 378,636, filed February 12, 1941.

When analyzing a mixture (which originally may be gaseous, liquid or solid) with a mass spectrometer, the mixture is introduced from a sample region into an ionization region in gaseous or vapor form. In the ionization region, molecules of the mixture are ionized in characteristic ways under controlled conditions by subjecting them to the ionizing action of particles such as electrons. Such electrons are commonly directed by the action of an electric field into the ionization region where they encounter and ionize molecules of the mixture. The ions formed are then withdrawn into an analysis region where ions of different mass-to-charge ratios are segregated into beams which may be detected by successive focusing thereof upon an ion collector. As the beams are successively detected at the collector, the beam intensities may either be measured directly with a suitable indicator or else automatically and permanently recorded prior to measurement. The peak intensities of the ion beams are representative of either the amounts of the withdrawn ions or the rates of formation of the respective ions. Such a record or set of measured peak intensities forms a mass spectrum.

For simplicity, the ionization of a sample by particles having a given amount of energy corresponding to the kinetic energy of electrons which have been accelerated by some predetermined voltage will be referred to simply as ionization of the sample or component at that voltage.

Either before or after a mass spectrum of a mixture has been obtained, reference samples containing different proportions of the components that may be present in the mixture or substances corresponding chemically thereto are similarly subjected to analysis in a mass spectrometer under substantially the same ionizing conditions to which the mixture was subjected, and corresponding mass spectra obtained for the reference samples. Usually, though not necessarily, the reference samples are relatively pure samples of the respective components that may occur in the mixture.

The composition of the mixture is then determined by comparing the mass spectrum of the

mixture with the mass spectra of the reference samples. Such a comparison is most simply carried out by a mathematical procedure involving the comparison of the peak intensities of the beams forming the spectra.

In practice, the analysis of such a mixture is greatly facilitated if the intensity of each peak occurring in the mixture spectrum represents the sum of the intensities of corresponding peaks 10 that would be obtained in mass spectra of the separate components if present alone. A method for producing this effect, which is known as linear superposition, is disclosed and claimed in copending patent application, Serial No. 320,802, filed by Harold W. Washburn and Daniel Dwight Taylor. Briefly, this method involves maintaining the sample in a sample chamber homogeneous at all times during analysis, flowing the components from the sample chamber into an ionization chamber through a gas inlet at mutually independent rates, ionizing each component in proportion to its partial pressure in the ionization chamber and independently of the amounts of the other components there, and providing such pressure conditions in the mass spectrometer that collisions between ions withdrawn from the ionization chamber with any molecules, either in the ionization chamber or in the analyzing chamber, are relatively infrequent.

When conditions suitable for achieving linear superposition during the analysis of a mixture are obtained, the intensity of any peak occurring in the mass spectrum of the mixture due to ions of mass-to-charge ratio m produced at a voltage V 20 may be represented by the following equation:

$$I_{V^m} = \sum_i v P_i^m X_i$$

where

X_i = the partial pressure of component i in the mixture and

$v P_i^m$ = a sensitivity coefficient representing the efficiency of the mass spectrometer in producing ions of mass-to-charge ratio m obtained from component i by particles having an ionization energy of V electron volts.

The sensitivity coefficient may be expressed as the ratio of the number of divisions of measured peak height or the number of units of beam intensity per micron (μ) of partial pressure of 40 component i present in the chamber. Values of the sensitivity coefficients may be most readily determined from the intensities of the beams occurring in the mass spectra obtained from pure components.

In the event that linear superposition is not achieved, the analysis of the mixture may be made by obtaining mass spectra of known mixtures approximating the unknown in composition and comparing the spectrum of the unknown 50 mixture with the spectra of the known mixture

by the interpolation method which is more fully explained in copending patent application, Serial No. 324,950, filed March 20, 1940, by Daniel Dwight Taylor.

For simplicity, I shall discuss the application of my invention under conditions such that linear superposition is maintained.

The amount of ions of mass-to-charge ratio m originating from a given component i is found to vary over a wide range with changes in the ionizing voltage. By plotting such amounts against the corresponding voltages, ionization curves for the particular ions and component in question are obtained.

The ionization curves of ions of a given mass-to-charge ratio formed from different components which may be present in a mixture, are not generally of the same shape. Nor are the ionization curves of ions of different mass-to-charge ratios formed from the same component of the same shape.

According to the present invention, I ionize the mixture at voltages at which such ions are formed in different proportions from different components, measure the amounts of ions of such mass-to-charge ratio formed at each voltage, and utilize those measurements in determining the composition of the mixture.

My invention may be applied, for example, to the analysis of mixtures containing hydrocarbon isomers, which generally produce ions of the same mass-to-charge ratios, and to mixtures containing other components of the same molecular weights.

Accordingly, the principal object of my invention is to provide an improved method for analyzing chemical mixtures with a mass spectrometer.

My invention possesses numerous other objects and features of advantage, some of which together with the foregoing will be set forth in the following description embodying and utilizing my novel method. It is therefore to be understood that my invention is applicable to analyses of a variety of mixtures and to other mass spectrometers of various types or which may utilize other kinds of ionizing particles, and that I do not limit myself, in any way, to the analyses, to the apparatus, or to the ionizing particles, of the present application, as I may adopt various other modifications of my invention utilizing the method, within the scope of the appended claims.

My invention may be more readily understood by direct reference to the drawings in which:

Fig. 1 shows a general organization of a mass spectrometer to which my method may be applied.

Fig. 2 is a schematic drawing partly showing a section taken on a line 2-2 of Fig. 1 of part of the mass spectrometer including the ionization chamber and the ionization energy controls.

Fig. 3 is a graph showing ionization curves of a mixture of two components and of the components alone.

Referring to the drawings:

In Fig. 1, I have shown a sample chamber 1 connected to an ionization chamber 3 through a tube 5 containing a gas inlet 7 which may be in the form of a capillary leak or restricted orifice. A gas sample to be analyzed is introduced when the mass spectrometer is in condition for operation into the ionization chamber through said inlet. A T shaped conduit 10 is connected to the sample chamber 1. One branch of the T is connected to a vacuum pump through a valve 11. The other branch of the T has a valve 9 through

which a sample may be admitted. A pressure gauge, for example a McLeod gauge 13, is connected to the sample chamber. A valve 15 is provided in the line 5 which connects the sample chamber to the ionization chamber.

As illustrated in Figs. 1 and 2, electrons emitted from a heated filament 17 are directed in a beam 18 through aperture 19 in the electron beam intensity control electrode 21, through aperture 23 in electron accelerating electrode 25 which is formed by part of the wall of said ionization chamber 3, and through aperture 27, in the opposite portion of the wall of said ionization chamber, said beam being directed along the line perpendicular to the face of a magnetic pole 29 by the combined action of the magnetic field indicated by arrow 31 in Fig. 2, which field is directed downward perpendicular to the plane of the drawing in Fig. 1, and electric fields parallel to the magnetic field. The electrons passing through said apertures impinge on electron catcher 32 electrically connected to electrode 25. The electric fields are provided by potentials applied from voltage supply circuit 33 to filament 17 and electrodes 21 and 25. Said voltage supply circuit includes means for varying the relative potentials between said filament and said electrodes.

One way of accomplishing this variation is to connect the filament to the negative ends of a pair of parallel connected rheostats 35 and 37 through which currents flow from a battery 39, and to connect said electrodes 21 and 25 to rheostats 35 and 37 respectively through sliding contacts 36 and 38 for picking off suitable positive potentials.

When electrons in said electron beam 18 bombard molecules of the sample in the ionization chamber, positively charged ions are formed in amounts characteristic of the structure of the molecules and in amounts proportional to the electron beam intensity. The amounts of ions produced are dependent on the energy of the electrons in beam 18.

The positive ions formed are accelerated toward first slit electrode 41 by action of a small electric potential which maintains said first collimating slit electrode negative with respect to a pusher electrode 43 on the opposite side of said electron beam. Some of the accelerated ions pass through a narrow slit 45 in said first collimating electrode 41 and are thereupon accelerated by a large negative potential between said first collimating slit electrode 41 and second collimating slit electrode 47. Some of the accelerated ions then pass through a second slit 49 in said second collimating slit electrode.

The ions thus pass through slit 49 at a high velocity. The path they take, however, is not straight but curved, owing to the action of the magnetic field. The radius of curvature of the path for a given accelerating voltage depends upon the mass-to-charge ratio of the respective ions. Hence, ions of a given mass-to-charge ratio will follow one curved path, while those of a higher mass-to-charge ratio will follow another curved path of greater radius. By proper adjustment, either of the magnetic field, or of the accelerating voltage, or of both, ions of any desired mass-to-charge ratio can be made to follow a predetermined radius of curvature and thus be focused at exit slit 51, positioned in front of an ion collector 53. When a beam containing ions of predetermined mass-to-charge ratio impinges on collector 53, a corresponding ion cur-

rent is produced, which current may be measured by a suitable vacuum-tube amplifier 55 and galvanometer 57, or recorder (not shown).

In order to obtain a mass spectrum of a sample, beams of different mass-to-charge ratios are successively moved past said collector slit 51 by changing voltages supplied to said pusher electrode 43, and said collimating slit electrodes 41 and 47, by electrical connection to suitable points of a potential divider 60 in ion beam deflection control circuit 61. This may be done most readily by changing the voltage across said divider 60 by adjustment of a sliding potentiometer contact 67 connected to one end thereof. When beams comprising ions of different corresponding mass-to-charge ratios are successively focused at said exit slit 51, ions in the different beams are successively discharged at the ion collector 58, the respective intensities of corresponding ion currents are read on galvanometer 57.

Experiment shows that if the ionizing voltage is raised above a certain critical point, each gas or vapor can be made to produce ions of several different masses. The number of ions of each mass produced depends on the type and quantity of gas or vapor, and on the voltage of the ionizing electrons. In other words, each gas or vapor has an ionization or cracking pattern, which is a function of the ionization voltage. From a knowledge of these cracking patterns and their variation with ionization voltage, together with a knowledge of isotope ratios and packing fractions of the ions recorded, the quantities of the various gases and vapors present in the unknown sample can be determined. However, it is usually unnecessary to take all these factors into account in a single analysis.

According to the present invention, I take advantage of the fact that the relative amounts of a given type of ion produced from different components generally varies with the ionization potential. Thus, for example, I may determine the composition of a normal butane-isobutane mixture by measuring the number of ions of a single mass-to-charge ratio derived from such a mixture at two different ionization voltages. By comparing these results with measurements obtained from pure components under low pressure conditions such as those already hereinabove described, I may compute the quantities of normal-butane and isobutane from equations similar to equation 1. My method may, of course, be applied to mixtures of gases other than hydrocarbons.

In order to determine how the intensity of any particular ion beam varies with the energy of the electrons in the electron beam, I adopt one of two procedures. In the first, the total accelerating voltage to which ions are subjected may be set at a predetermined value by adjustment of the total potential between pusher electrode 43 and collimating slit electrodes 41 and 47 by suitable positioning of the slide contact 67 on potentiometer 69 in the deflection control circuit 61, thereby focusing ions of any predetermined mass-to-charge ratio desired at the exit slit 51. With the mass spectrometer adjusted to detect ions of predetermined mass-to-charge ratio, the energy of the electrons in the electron beam may be adjusted to successively different values indicated by voltmeter 66 and the corresponding intensities of the ion beam measured by means of galvanometer 57. This procedure is

repeated for each peak of interest in each component of interest. In the second procedure I set contact 38 successively at different points of rheostat 37 to establish different values of electron accelerating voltages as indicated by a voltmeter 66, and obtain a mass spectrum of the sample under investigation at each of these voltages for each component in which I am interested, by the method hereinabove described.

In both of these methods the voltage between the filament 17 and the electron beam intensity control electrode 21 is maintained constant and preferably at a value such that the total electrical current borne by electron beam 18 is constant.

In Fig. 3, I have plotted typical ionization curves *a* and *b* for ions of the same mass-to-charge ratio obtained from equal amounts of two pure components. The appearance potentials, that is the potentials below which no ions are formed, differ between the respective components in this case. Curve *c* is a plot of the ratio of the amounts of ions formed from the two components at the respective voltages. Curve *d* is a curve obtained for such ions from a mixture containing half of said amount of each component. Though the ionization curves of the individual components are relatively smooth, the curve *d* for the mixture has a sharp bend at point *p*, giving an indication of the character of the mixture. While the composition of the mixture may be determined by comparison of curves *a*, *b*, and *d*, the analysis of the mixture may be made more simply by solving a pair of simultaneous equations, of the type given in Equation 1 above, corresponding to two voltages at which the components produce such ions in different proportions. For example, if the respective ion beam intensities of a sample of the mixture and samples of the components are measured at both, 50 volts and 20 volts, and these are the only two components present in the mixture, the following relations hold:

$$I_{50}^m = {}^{50}P_1^m X_1 + {}^{50}P_2^m X_2 \quad (2)$$

$$I_{20}^m = {}^{20}P_1^m X_1 + {}^{20}P_2^m X_2 \quad (3)$$

where the subscripts "1" and "2" refer respectively to two different components. The mass-to-charge ratio of the ions in the beam is *m*.

If the sensitivity coefficients for the first component at the two voltages are

$${}^{50}P_1^m = 13.7 \quad (4)$$

and

$${}^{20}P_1^m = 4.76 \quad (5)$$

and the sensitivity coefficients for the second component at the two voltages are

$${}^{50}P_2^m = 5.21 \quad (6)$$

and

$${}^{20}P_2^m = 3.32 \quad (7)$$

then

$$X_1 = 0.163 I_{50}^m - 0.252 I_{20}^m \quad (8)$$

and

$$X_2 = 0.662 I_{50}^m - 0.230 I_{20}^m \quad (9)$$

If in a particular instance the intensity of the beam obtained for the mixture at 50 and 20 volts respectively are:

$$I_{50}^m = 215.7 \quad (10)$$

and

$$I_{20}^m = 109.5 \quad (11)$$

the amounts of the components present in the mixture will be

$$X_1 = 7.56$$

and

$$X_2 = 22.8$$

My invention may, of course, be applied to cases in which more than two components are present in the mixture. It may even be applied if more than two components produce ions of the same mass-to-charge ratio. In this case a number of variations of my invention will naturally occur to those skilled in the art, in view of the foregoing explanations. For example, an analysis of a three-component mixture may be made readily by measuring the intensity of a single ion beam at three voltages, if the shapes of the ionization curves are sufficiently different for the three components. In the event that the shapes of the ionization energy curves for two components are the same for a particular ion beam to which another component having an ionization curve of different shape makes a contribution, additional data are necessary in order to perform a complete analysis. Such additional data may be in the form of ion beam intensity and sensitivity coefficients for ions of another mass-to-charge ratio, applicable to the mixture and its components. In any case it will be clear that an analysis containing n -components may be obtained from computations based on n independent measurements obtained in a mass spectrometer on the mixture, provided, of course, corresponding data for the individual components are known or determined.

From the foregoing description it is seen that I have provided a new method of mass spectrometry which makes possible the determination of the amounts of a greater number of components present in a mixture than there are ions of different mass-to-charge ratios measured.

I claim:

1. In the analysis of a mixture containing a plurality of components involving the comparison of measurements of the quantities of ions of predetermined mass-to-charge ratios formed in a

mass spectrometer from said mixture and from reference samples including different proportions of the components under the same ionization conditions, the improvement which comprises separately ionizing said mixture at different ionization voltages at which ions of one such mass-to-charge ratio are formed in different proportions from the respective components, and measuring the amounts of such ions formed at each said voltage from the mixture and from the several reference samples.

2. In the analysis of a mixture by mass spectrometry the improvement which comprises bombarding the mixture with an electron beam having a potential such that ions of a common mass-to-charge ratio are formed from a plurality of components in the mixture, bombarding the mixture with an electron beam having a different potential but one such that ions of the common mass-to-charge ratio are formed from the same components, but the proportions of the ions derived from the components being different than the proportions derived from these components at the other potential and measuring the amount of the ions of said common mass-to-charge ratio formed from the mixture at each ionization potential.

3. In the analysis by mass spectrometry of a mixture containing a plurality of components the ions of which have the same mass-to-charge ratio, the improvement which comprises bombarding the mixture with an electron beam so that the plurality of components produce the ions of the same mass-to-charge ratio, then bombarding the mixture with an electron beam having a different potential than under the first-mentioned bombardment, thereby creating the ions of the same mass-to-charge ratio such that the ions of the plurality of components are in a different ratio to each other than when under the first-mentioned bombardment and measuring the amount of the ions of said mass-to-charge ratio formed from the mixture at each ionization potential.

REED C. LAWLOR.
